UNITED STATES PATENT OFFICE.

GEORGE W. PACKER, OF ROCK FALLS, ILLINOIS.

HOOP-DRIVER.

SPECIFICATION forming part of Letters Patent No. 325,440, dated September 1, 1885.

Application filed April 30, 1885. (No model.)

To all whom it may concern:

Be it known that I, GEORGE W. PACKER, a citizen of the United States, residing at Rock Falls, in the county of Whiteside and State of Illinois, have invented certain new and useful Improvements in Trussing Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention pertains to machines for driving the truss-hoops upon barrels, pails, tubs, and butter-casks; and it consists, first, in novel mechanism for pressing such hoops to place, and second, in novel provisions for adjusting such machine to the various sizes of vessels it will be required to operate on.

In the drawings, Figure 1 is a front elevation of a machine embodying my invention, a partial tub being shown in position for operation. 25 Fig. 2 is a side elevation exhibiting the method of actuating the crank-head N, which drives the pitman P. Fig. 3 is a plan of the horizontal head R to which the drivers S T are attached. Fig. 4 is an end view of the 30 cams C and E.

A A are the supporting posts, suitably attached to the base-plate A', and joined at their upper extremity by the cross-beam B and midway by the cross-beam B'.

35 C is a cam hinged at its upper end to the center of the cross-beam B, and hinged at the lower end of its short side to the toggle D. The other end of the toggle D is hinged to the long end of the cam E. The cams C and 40 E have segmental opposing faces, and one short side, a, and one eccentric or long side, b, and are so relatively placed that when such cams are oscillated laterally, their opposing faces engage throughout their entire length.

45 The opposing faces of the cams C and E are provided with slots d, which receive the toggles D in the oscillation of such cams. The lower end of the cam E is hinged to the top of the vertical shaft F, which latter is sleeved 50 in and traverses vertically the center of the central cross-beam B'. The cams C and E are oscillated laterally and the shaft F caused to

reciprocate vertically by the following described mechanism:

G is a rotating shaft journaled transversely 55 of the machine upon the brackets H, attached, respectively, to the rear of the posts A. The shaft G can be driven from the belt-pulley G', affixed thereon, or in any other suitable manner.

60 J is a short rotating shaft journaled on one of the brackets H transversely of and directly over the shaft G. Immediately above the shaft G a small gear, K, is loosely placed on the shaft J. This gear K is engaged and continuously rotated by a worm-gear, e, on the shaft G. The outer end of the hub of the gear K is furnished with ratchets f. Adjacent to and outside of the gear K the clutch L is feathered to the shaft J. The inner face 65 of the clutch L is fitted to engage the ratchets f of the gear K, and by means of the short vertical lever M, pivoted on the bracket H directly below the clutch L, and with its upper end forked so as to loosely engage and 70 traverse the annual recess g in the exterior of such clutch, the latter is, at will, thrown into and out of engagement with the gear K. When thus engaged the gear K imparts a 75 rotary movement to the shaft J, and to the crank-head N, rigidly seated on the inner end of the shaft J. A horizontal transverse pitman, P, is pivotally attached at its outer end to the inner side of the crank-head N, and at its inner end is pivotally attached to the farther or longer end of the cam E and above 80 the pivotal point of the latter. The direction of rotation of the crank-head N is from the point of attachment thereto of the pitman P, upward and outward, and has the effect of 85 drawing the long end of the cam E under the cam C, and forcing downward the loose vertical shaft F. The toggle D imparts the lateral oscillation of the cam E to the cam C, and thus doubles the downward movement of the shaft 90 F. Such toggle D not only insures the coincident movement of said cams, but also holds the latter in prescribed though varying mutual relation. If preferred, the opposing faces of the cams C and E can be cogged or corrugated transversely, so as to engage and actuate 95 each other, in which event the toggle D may be omitted. The outer end of the pitman P is adjustably attached to the crank-head N in

the radial slot h in the latter, and the length of the stroke of such pitman thereby regulated to adjust the movement of the shaft F to suit tubs of various lengths.

5 R is a horizontal circular head, rigidly attached at its center to the lower end of the shaft F . To the lower face of the head R are adjustably attached four downwardly-extending equidistant drivers—one front one, S , and 10 three side and rear ones, $T T T$. These drivers S and T are each attached to the head R by means of screw-bolts x , seated, respectively, in radial slots i in such head, and screwed downward into threaded sockets in the top of 15 such drivers. By this means the drivers may be adjusted to and from the center of the head R , so as to be adapted to tubs of different diameters.

In Fig. 1 is shown the outline of a tub with 20 the truss-hoops thereon in position for being driven. On the inner faces of the drivers S and T are formed transverse recesses k , having upper abrupt or horizontal walls to receive and engage their proper truss-hoop.

25 The recesses k are adjustable vertically to suit the varying conformation of different tubs by means of clamps V , which forms the abrupt or working wall of such recess. The clamps V have horizontal corrugations m on their outer 30 faces, which fit into corresponding corrugations n in the contiguous face of the driver, and are fastened to the latter by transverse bolts p . By loosening the bolts p the clamps V may be adjusted vertically, and the recesses 35 K given any desired altitude. The front driver, S , is provided with the hinge r , so as to be swung out of the way in placing or removing the tub.

40 W is the pedestal or base which supports the tub, and is provided with the annular recesses t around its exterior, each of which is adapted to support a tub of a certain diameter. The base W decreases in diameter in conical form toward its top, so as to be accommodated to tubs of varying diameters and 45 length, it being the fact that tubs of less diameter have also less length. The posts A are attached to the cross-beam B by passing through the ends of the latter, and are threaded from a short distance above to a short distance below such beam. Nuts v and w are placed on the posts A , respectively above and 50 below the beam B , and thus the altitude of the beam B can be adjusted to bring the cams C and E into proper mutual relation and assist 55 in regulating the stroke of the shaft F . A rope, 1, is attached to the head R and passed over a pulley, 2, on the beam B , and furnished with a sufficient weight, 3, at its free end, and 60 serves to elevate the head R to position for the succeeding downstroke after the clutch L is disengaged, or such head may be raised by the hand of the operator. Each of the recesses t and the base-plate A' present a uniform horizontal surface to sustain the tub, and the top of 65 the latter is thereby held in line and the top

of all the staves in the same plane. The tub is inverted over the base W and rested upon the plate A' or such recess t as will bring it in proper relation to the drivers S and T . The clutch L is then thrown into engagement with gear K and the recesses k forced down upon the truss-hoops until the latter are driven to their proper position, when the clutch L is disengaged and the tub removed. The hoops 75 when thus driven maintain their relative position, are held horizontal, and can be driven to any desired degree of tightness. But one operation is necessary for each tub.

What I claim as my invention, and desire 80 to secure by Letters Patent of the United States, is—

1. The combination of the cam C , hinged at its upper end to the fixed beam B , the cam E , hinged at its lower end to the reciprocating 85 shaft F , the shaft F , sleeved in the beam B' , the head R , provided with drivers $S T$ and affixed to such shaft, and suitable mechanism for oscillating said cams, substantially as shown, and for the purpose described. 90

2. The combination of the cam C , hinged at its upper end to the fixed beam B , the cam E , hinged at its lower end to the reciprocating shaft F , the toggle D , pivotally connected at each end to the engaging faces of the cams 95 $C E$, the shaft F , sleeved in the beam B' , the head R , provided with drivers $S T$ and affixed to such shaft, and suitable mechanism for oscillating said cams, substantially as shown, and for the purpose described. 100

3. The combination of the crank-head N , actuated in any suitable manner, the pitman P , connecting said crank-head with cam E , the cam C , hinged at its upper end to the beam B , the cam E , hinged at its lower end to 105 the reciprocating shaft F , the shaft F , sleeved in the beam B' , the head R , provided with drivers $S T$ and affixed to such shaft, the whole in suitable relation to means for supporting the tub, substantially as shown, and 110 for the purpose described.

4. The base W , provided with the ascending series of annular recesses t , and placed in suitable relation to a descending driving-head, R , provided with radially-adjustable drivers 115 $S T$, and suitable mechanism for actuating such head, substantially as shown, and for the purpose described.

5. The combination of the base A' , posts $A A$, cross-beam B' , shaft F , sleeved in such 120 cross-beam, head R , provided with drivers $S T$, and suitable mechanism for reciprocating such shaft in a vertical direction, substantially as shown, and for the purpose described.

In testimony whereof I affix my signature in presence of two witnesses.

GEORGE W. PACKER.
